UNITED STATES PATENT OFFICE

2,437,771

STACK

Clyde F. Wait, Flint, Mich., assignor to Palace Corporation, Flint, Mich., a corporation of Michigan

Application December 6, 1943, Serial No. 513,081

2 Claims. (Cl. 98—84)

1

The invention relates to stacks for the discharge of products of combustion and has more particular reference to a construction designed for use on low one-story structures such, for instance, as automobile trailers.

It is the primary object of the invention to guard against down drafts which frequently occur with constructions heretofore used and which with a heater using a gas or oil flame may extinguish the same. With this object in view the invention consists in the construction as herein-after set forth.

In the drawings:

Fig. 1 is a vertical central section through my improved stack;

Fig. 2 is a top plan view thereof;

Fig. 3 is a vertical central section through the portion of the stack passing through the roof and showing the thermal insulation for the same;

Fig. 4 is a cross section on line 4—4, Fig. 3.

As illustrated in Fig. 1, A is a substantially cylindrical stack extending upward above the roof of the building. B is a conical cap which is connected to and spaced from the upper end of the stack A by strips C, said cap extending radially beyond the member A to form protecting eaves. D is a cylindrical sleeve surrounding and spaced from the stack A being connected thereto by vertically extending webs or bracket members E. The sleeve D extends above the eave portions B' of the cap B and is then provided with an inwardly contracting conical portion F which extends above the apex of said conical cap. At its lower end the sleeve D is open but is provided with an annular bead G for imparting rigidity thereto. Below and spaced from the lower end of the sleeve D is a conical flange H which surrounds and is secured to the stack A. At the upper end of the stack A is a flaring conical flange I. The portion of the stack passing through the roof is surrounded by a second sleeve J which is open at its lower end to the interior of the house while its upper end extends adjacent to a conical flange H' terminating in an outwardly flaring portion K. A depending flange L at the end of the flange H' overlaps the flange K while leaving a sufficient air passage for the escape of air from the space between the sleeve and the stack.

With the construction as described any down draft current through the stack is effectually prevented. Thus, any external air current which may enter through the contracted top of the sleeve B will be directed downward outside of the eaves portion B' and will escape through the open

5 lower end of the sleeve. On the other hand, any external current striking against the conical flange H will be directed upward through the sleeve D, while the flaring flange I will direct 10 such current away from the open upper end of the stack so as to pass outside of the eaves portion B' escaping through the top. The conical flange H, flaring flange I and contracting conical flange F cooperate with each other to normally 15 cause any laterally directed air current to pass in an upward direction through the sleeve D thereby constituting an ejector which draws gas outward from the top of the stack instead of permitting any inward movement thereof.

15 This construction of stack has been thoroughly tested under various conditions of the external atmosphere and in every case has prevented the formation of any down current through the portion A.

20 What I claim as my invention is:

1. A stack comprising a cylindrical portion extending upward above the roof of the building, a conical cap spaced above and secured to said cylindrical portion to extend radially beyond the 25 same forming projecting eaves, a cylindrical sleeve surrounding and spaced from said cylindrical portion to overlap and extend parallel thereto for a large portion of its length being also spaced from the outer edge of the eaves portion of said cap and extending above the same, said sleeve being open at its lower end, an outwardly flaring flange at the upper end of said cylindrical portion for directing any upward current in the sleeve outward beyond said eaves, a 30 conical contracting portion at the upper end of said sleeve extending above the apex of said conical cap, a conical flange surrounding said cylindrical portion below the lower end of said sleeve for directing current upward through the latter, 35 a second sleeve surrounding the portion of said cylindrical portion which passes through the roof and forming a heat insulation for the latter, said second sleeve extending upward beneath said last mentioned conical flange and spaced therefrom for the escape of air therethrough.

40 2. A stack comprising a cylindrical portion extending upward above the roof of the building, a conical cap spaced above and secured to said cylindrical portion to extend radially beyond the same forming projecting eaves, a cylindrical sleeve surrounding and spaced from said cylindrical portion to overlap and extend parallel thereto for a large portion of its length being also spaced from the outer edge of the eaves portion 45 of said cap and extending above the same, said

3

sleeve being open at its lower end, an outwardly flaring flange at the upper end of said cylindrical portion for directing any upward current in the sleeve outward beyond said eaves, a conical contracting portion at the upper end of said sleeve extending above the apex of said conical cap, a conical flange surrounding said cylindrical portion below the lower end of said sleeve for directing current upward through the latter, a second sleeve surrounding the portion of said cylindrical portion which passes through the roof and forming a heat insulation for the latter, said second sleeve extending upward beneath said last mentioned conical flange and having an outwardly flaring flange beneath and slightly spaced from said conical flange, and said conical flange having a depending flange surrounding said flaring flange.
